CLAIM

The ornamental design for a modular biological fluid analyzer, as shown and described.

DESCRIPTION

FIG. 1 is a perspective view of a modular biological fluid analyzer, showing our new design;

FIG. 2 is a front elevational view thereof;

FIG. 3 is a side elevational view thereof;

FIG. 4 is a side elevational view thereof, opposite that shown in FIG. 3;

FIG. 5 is a top plan view thereof;

FIG. 6 is a rear elevational view thereof;

FIG. 7 is a bottom plan view thereof;

FIG. 8 is a perspective view thereof, the broken line showing being for illustrative purposes only and forming no part of the claimed design;

FIG. 9 is a perspective view of a second embodiment of the modular biological fluid analyzer, showing our new design;

FIG. 10 is a front elevational view thereof;

FIG. 11 is a side elevational view thereof;

FIG. 12 is a side elevational view thereof, opposite that shown in FIG. 11;

FIG. 13 is a top plan view thereof;

FIG. 14 is a rear elevational view thereof;

FIG. 15 is a bottom plan view thereof; and,

FIG. 16 is a perspective view thereof, the broken line showing being for illustrative purposes only and forming no part to the claimed design.
